FLOORING JACK

Jacob Sholick, Johnstown, Pa.

Application June 13, 1955, Serial No. 515,116

4 Claims. (Cl. 254—12)

This invention relates to a flooring jack of the rack and pinion type and more particularly to a jack capable of exerting either a "pushing" or "pulling" force on the flooring being laid.

Flooring jacks of the rack and pinion type have heretofore been employed, intended for effecting a tight fit between adjacent floor boards, illustrative of which are the jacks of the following patents: 201,709, Schofield, March 26, 1878; 1,186,277, Burridge, June 6, 1916; 1,447,720, Hall, March 6, 1923.

Some jacks of this type are of complex construction and often very cumbersome to handle. Another shortcoming is the failure to provide for positioning the jack on the sub-floor while pushing a floor board into proper position. The limited jacking movement of these devices also is a hindrance in certain phases of the floor laying operation.

It is within the contemplation of the present invention to embody in a single flooring jack, all features essential to facilitate laying of floor boards. The principal object of this invention therefore is to provide a compact flooring jack of simple construction, capable of exerting either a "pushing" or a "pulling" force on the floor being laid.

Another object is to provide a flooring jack especially adapted to be positioned on a sub-floor when exerting a "pushing" force on the flooring, the jack having a longer jacking movement than has heretofore been possible.

A further object is to provide a flooring jack of the character described including a rack bar adapted for engagement with the beading of the floor being laid, the bar being actuated by a ratchet wheel, the direction of movement of the ratchet wheel and rack bar being selectively controlled by a spring actuated yoke member.

Other objects of the invention will be manifest from the following description of the present preferred form of the invention, taken in connection with the accompanying drawings, wherein:

Fig. 1 is a side elevational view of a flooring jack of the present invention, without the puller assembly, illustrating its application in exerting a pushing force on flooring being laid;

Fig. 2 is a top plan view of a flooring jack constructed in accordance with the present invention, with a portion of the handle removed;

Fig. 3 is a side elevational view of the device of the present invention, a portion thereof being broken away to disclose details of construction, and illustrating the application of the present invention in exerting a pulling force on flooring being laid; and

Fig. 4 is a side elevational view of the yoke forming a part of the present invention.

Referring now in greater detail to the drawings, the numeral 5 generally designates a base assembly for the flooring jack and includes a bottom 6 and side members 7 and 8. Base assembly 5 is of substantially U-shape cross section and the lower extremity of sides 7 and 8 are rabbeted to receive flanges 9 of a rack bar 10. Rack

2

bar 10 is provided through approximately three-quarters of its length with transversely disposed ribs 11 adapted to mesh with the complementary teeth 12 of a ratchet wheel 13. The outer terminal of rack bar 10 is provided with a groove 14 adapted to engage the beading 15 of floor board 16, the latter being positioned in sub-flooring 17.

Ratchet wheel 13 is mounted on an axle 18, the terminals of which latter are journaled in side members 7 and 8 respectively. A handle or lever 19 is provided for imparting rotation to wheel 13. One end of said handle or lever is bifurcated, the furcations 20 thereof straddling the wheel 13 and having terminal openings in which the axle 18 is loosely mounted. As shown in the drawings, the furcations are within the sides 7 and 8 of the base assembly. Pivotaly mounted on a pin 21 which spans the furcations 20 near the upper limit thereof, is a yoke shape pawl 22 which includes curved terminals 23 and 24. These terminals are adapted to be selectively engaged with ratchet wheel 13 to effect movement of rack bar 10 in either direction upon operation of lever 19. To normally engage the pawl with teeth 12 of ratchet wheel 13 there is provided a fixed wire spring 25 which is convoluted on pin 21 with one end flexed into engagement with a terminal of the pawl. For the purpose of retracting rack bar 10 there is provided a flat spring 26 mounted on lever 19 and longitudinally slideable on said lever by actuation of a thumb piece 27. Spring 26 is held in place by a pair of spaced straps 28 carried by lever 19. The ends of the pawl are selectively engaged with the ratchet wheel, at the option of the user, through longitudinal movement of the spring 26 in an obvious manner.

A suitable locking unit is provided to prevent backward movement of rack bar 10 when it is being pushed against the floor board as illustrated in Fig. 1. This unit includes a shaft 29, which is suspended by sides 7 and 8 above rack bar 10, and an elongated spring pressed detent 30, the latter spanning the distance between said sides 7 and 8. The detent is urged into engagement with ribs 11 by its spring 31, the spring being anchored to side 8. A release 32 is provided, which is actuated by an arm 33 to disengage the detent, when rack bar 10 is to be retracted.

When the flooring jack of the present invention is being utilized to push a floorboard into place, it is anchored by means of movable cleats 34 pivotally mounted on sides 7 and 8 adjacent the aft end of the device, the cleats being provided with sharply pointed feet 35 which are forced into sub-flooring 17. The cleats 34 are held in position by catches 36, also pivoted to sides 7 and 8 respectively.

In Fig. 3 there is illustrated the use of the present invention to exert a pulling force on flooring being laid. For effecting this force, sides 7 and 8 are provided near their forward end with a plurality of vertical dovetail slots 37 adapted for the reception of a removable and adjustable puller assembly 38. This assembly comprises a substantially U-shaped member 39, the terminals of which are provided with dove-tail protrusions 40 complementary to, but slightly smaller than the dove-tail slots 37. This permits a slight "play" of puller assembly 38 relative to the jack base, in order to "work" adjacent floor boards into contiguous relationship. A cross piece, forming a part of member 39, is slotted, near its upper end at 39' to permit passage of rack bar 10 therethrough to serve as a guide when the rack bar is being used for pulling flooring into place. As shown to advantage in Fig. 3, the cross piece of U-shaped member 39 is thickened at 41 and one face of the thickened portion is grooved at 42 to allow engagement of the puller member with floor-board 16. This structure permits use of the puller at

tachment adjacent a wall 43 where there is insufficient room to use the jack as a pusher.

In actual use the majority of the flooring being laid is pushed into position by using the jack in the manner illustrated in Fig. 1. Spring 26 is alternately engaged and disengaged with pawl 22 to effect corresponding engagement of either end of the pawl 22 with the teeth 12 of ratchet wheel 13. By operating lever 19 back and forth, rack bar 10 is moved fore or aft, depending upon the position of the spring 26 and release arm 33.

As shown to advantage in Fig. 3, when the flooring is laid to a point adjacent a wall 43, where space will not permit pushing the flooring into place, puller attachment 38 is employed with portions 40 being engaged in whichever pair of dove-tail slots 37 are most suitable. The beading 15 of flooring 16 is fitted into groove 42 and rack bar 10 is moved into engagement with wall 43. Cleats 34 are swung out of anchoring engagement with flooring 16. Then rack bar 10 is moved forward by manipulation of handle 19, and the pushing force thereof against wall 43 effects a backward sliding movement of base assembly 5 and puller assembly 38 to pull floorboard 16 into place.

While I have herein shown and described a preferred embodiment of my invention, it is nevertheless to be understood that various changes may be made therein, within the scope of the appended claims.

What I claim is:

1. A jack for laying boards in a flooring including a jack base adapted to be engaged with the sub-floor which are to receive the boards, a rack bar movably mounted in said base, one end of the bar being engageable with a board to be moved, means mounted on said base for imparting movement to the bar, the means comprising a ratchet wheel rotatably mounted on the base with a lever loosely mounted on the wheel axle, the lever carrying a yoke shaped pawl, the ends of which latter are selectively engageable with the ratchet wheel to effect a fore or aft movement of the rack bar, spring means engageable with said pawl for urging one terminal of the pawl into engagement with said ratchet wheel to effect forward movement of said rack bar, and means mounted on said lever movable into engagement with the other pawl terminal for urging the same into engagement with said ratchet wheel against the tension of said spring means, for effecting aft movement of said bar.

2. The same as claim 1 in which the lever has a bifurcated end, the furcations of which are loosely mounted on the wheel axle within the sides of the jack base.

3. A jack for laying boards in a flooring including a jack base adapted to be engaged with the sub-floor which is to receive the boards, a rack bar movably mounted in

said base, one end of the bar being engageable with a board to be moved, means mounted on said base for imparting movement to the bar, the means comprising a ratchet wheel rotatably mounted on the base, with a lever loosely mounted on the wheel axle, the lever carrying a yoke shaped pawl, the ends of which latter are selectively engageable with the ratchet wheel to effect a fore or aft movement of the rack bar, spring means engageable with said pawl for urging one terminal of the pawl into engagement with said ratchet wheel to effect forward movement of said rack bar, and a thumb operated spring member mounted on said lever and slidably longitudinally with respect thereto, into engagement with the other pawl terminal for urging the same into engagement with said ratchet wheel against the tension of said spring means, for effecting aft movement of said bar.

4. A jack for pushing and pulling floor boards into place including a jack base, a substantially U-shaped puller engaged with said base, a portion of said puller extending below the plane of said base and provided with a groove adapted to receive the beading of a floor board to be pulled into position, a rack bar mounted in said base and movable longitudinally with respect thereto, said rack bar extending beyond said puller to abut a fixed object for anchoring the bar when the puller is operated, and gear means mounted on said base in meshing engagement with said rack bar for effecting fore and aft movement of the latter at the option of the operator, said gear means comprising a ratchet wheel rotatably mounted on the base with a lever loosely mounted on the wheel axle, the lever carrying a yoke shaped pawl, the ends of which latter are selectively engageable with the ratchet wheel to effect a fore or aft movement of the rack bar, spring means engageable with said pawl for urging one terminal of the pawl into engagement with said ratchet wheel to effect forward movement of said rack bar, the gear means also including a thumb-operated spring member mounted on said lever and slidably longitudinally with respect thereto, into engagement with the other pawl terminal for urging the same into engagement with said ratchet wheel against the tension of said spring means, for effecting aft movement of said bar.
